UNITED STATES PATENT OFFICE

153,267

DESIGN FOR A SPECTACLE CASE

Robert E. Dingman, Indiana, Pa.

Application May 8, 1946, Serial No. 129,447

Term of patent 14 years

(Cl. D57—1)

To all whom it may concern:

Be it known that I, Robert E. Dingman, a citizen of the United States of America, residing in Indiana, in the county of Indiana and State of Pennsylvania, have invented a new, original, and ornamental Design for Spectacle Case, of which the following is a specification, reference being had to the accompanying drawing forming part thereof.

In the drawing:

Fig. 1 is a view of the end of the spectacle case, where the spectacles are inserted, showing my new design;

Fig. 2 is a side view;

Fig. 3 is an edge view; and

Fig. 4 is a view showing the end opposite to that shown by Figure 1.

I claim:

The ornamental design for a spectacle case, substantially as shown.

ROBERT E. DINGMAN.
